UNITED STATES PATENT OFFICE.

PHILIP F. REINHART, OF MERIDEN, CONNECTICUT.

CONCENTRATING MACHINE.

Application filed May 26, 1923. Serial No. 641,657.

To all whom it may concern:

Be it known that I, PHILIP F. REINHART, a citizen of the United States, residing at Meriden, in the county of New Haven and 5 State of Connecticut, have invented new and useful Improvements in Concentrating Machines, of which the following is a specification.

This invention relates to ore concentrating machines and contemplates a structure which eliminates the use of water in the separating process, and the rehandling of the water and wet ores as is now frequently necessary, the machine delivering the values 10 ready for the smelter without further treatment, and further separating material with a very small difference of specific gravity between the same.

Another important object of the invention resides in the provision of a machine wherein a suction chamber is employed and arranged within a rotatable drum, so that the lighter material can be separated from the heavier material as the drum is rotated, 15 means being provided for effecting an adjustment of the suction chamber so that the latter will efficiently operate to draw in particles varying in weight and size.

Other objects and advantages will appear 20 when the following detail description is read in connection with the accompanying drawing, the invention embodying a structure which is dustless in operation, and one requiring a minimum of horse power for 25 its operation, while the general simplicity and durability of the machine constitutes other important features of the invention.

In the drawings forming part of this application, like numerals of reference indicate similar parts in the several views, and 30 wherein:

Figure 1 is a side elevation of the invention.

Figure 2 is a sectional view taken on the 45 line 2—2 of Figure 1, looking in the direction of the arrows.

Figure 3 is a sectional view taken on the line 3—3 of Figure 2.

Figure 4 is a sectional view taken on the 50 line 4—4 of Figure 3.

Figure 5 is an enlarged fragmentary view showing the different positions of the suction chamber which is adjustable for the purpose above stated.

Figure 6 is a fragmentary view of the 55 casing.

Referring to the drawing in detail 10 indicates a casing mounted upon a suitable base 11, it being understood that the casing can vary in size and configuration without 60 departing from the spirit of the invention. This casing is provided with a door 12 by means of which access may be had to the casing when desired. Arranged upon the top of this casing is a drum 13 which is 65 slightly tapered toward one end and has its interior surface roughened in any suitable manner to effectively agitate the material introduced into the drum while the latter is being rotated. The drum is supported by spaced pairs of rollers, the rollers of each pair being indicated at 10' and arranged adjacent the opposite ends of the drum. These rollers operate in the space between the annular flanges 11', there being 70 a pair of these flanges for each pair of rollers as shown in Figure 1. An internal flange 14 is formed on the drum adjacent the intake end thereof and is utilized to feed the material evenly while the drum is 75 in operation, it being understood that the drum rotates very slowly. The material to be dealt with is arranged within the hopper 15, the latter being equipped with a valve 16 at the lower end thereof, and which valve controls the communication 80 between the hopper 15 and the supply tube 17 which leads from the lower end of the hopper into one end of the drum 14. The material in this manner is conveyed to the 85 drum, which is rotated as above stated, and it is during this operation of the drum that the lighter material is separated from the heavier material and drawn into the suction chamber arranged within the drum 14. 90 The heavier material is moved toward the large end of the drum and deposited in a trough or the like 18 which is mounted upon the top of the casing 10 and at an inclination to the latter, from which trough 95 the said material is conveyed to a suitable storage bin, or, in short, to its proper destination. It will be noted that when the material leaves the supply tube 17 and enters the drum it contacts with an apron 19 which 100 tends to spread the material as will be readily understood.

The suction chamber above referred to includes a flat top portion 20 and a curved corrugated and perforated bottom portion 21, the chamber is mounted upon an elbow 110 22 for partial rotation for a purpose to be

presently described, it being noted that said elbow connects the said chamber with the suction pipe 23 which passes through the top of the casing 10 and mounted for slideable and vertical adjustment thereon. A set screw 24 is used to hold the suction chamber in a given position after it has been rotated upon the elbow to meet certain requirements, it being apparent that the curved bottom 21 of this chamber corresponds to the curvature of the drum 14 in which it is arranged. In addition to being susceptible of being rotated upon the elbow 22, it is also mounted to be adjusted horizontally along this elbow, the set screw 24 being used in this instance to hold the suction chamber fixed with relation to the drum in a certain position. A lock nut 25 also holds the suction pipe 23 fixed with relation to the casing 10, notwithstanding the fact that this pipe is also capable of being adjusted vertically with a consequent adjustment of the suction chamber within the drum. This adjustment of the suction chamber is necessary to position it with relation to the drum in order to allow particles of different size and weight to be sucked into the chamber incident to the use of the machine. The suction for the chamber is created by a suction blower 26 having an air exhaust 27. The suction blower of course embodies a shaft 28 supporting a pulley 29 over which is trained a belt 30 so that the shaft and blower can be operated from any suitable source of power located at a remote point. As the material is turned over and over within the drum 14 as the latter rotates, the lighter particles are drawn into the perforated suction chamber 30 and conveyed into the casing A through the elbow 22 and the suction pipe 23, and this lighter material is deposited upon a baffle plate 31 arranged within the casing 10 sort of diagonally to overlie the suction pipe 23. The casing is provided with an outlet opening normally closed by a cover 32 which may be of a resilient character or held in its normal position by suitable resilient means indicated at 33 and to which closure the lower end of the baffle 31 is connected. So, when the weight of the material deposited upon the baffle becomes great enough to overcome the resilient means 33, the cover 32 is opened to allow the escape of this material from the casing 10. The casing is also provided with a valve 34 which may be adjusted to regulate the force of suction or draft through the suction pipe 23 and the suction chamber above described. Carried by the suction chamber just mentioned is a dust shield 36 which is arranged in close proximity to the discharge end of the drum 14.

While the drum may be rotated in any suitable manner, I preferably employ a

shaft 37 which is journalled in suitable bearings 37' as shown in Figure 1. The lower end of this shaft is provided with a bevelled gear 38 which meshes with a similar gear 40 carried by the adjacent end of the blower shaft 38. The upper end of this shaft 37 is provided with a worm gear 39. The other worm gear 39 meshes with a ring gear 42 carried by the drum, so that the latter is rotated simultaneously with the operation of the suction blower. The machine is very simple in construction and highly advantageous in operation for the purpose intended, and its use embodying all of the advantages herein above pointed out.

While it is believed that from the foregoing description, the nature and advantages of the invention will be readily apparent, I desire to have it understood that I do not limit myself to what is herein shown and described and that such changes may be resorted to when desired as fall within the scope of what is claimed.

Having thus described the invention, I claim:

1. An ore concentrating machine comprising a casing, a drum mounted for rotation thereon and adapted to receive the material to be dealt with, means for creating a suction in said casing, a perforated suction chamber horizontally disposed within the drum and communicating with said casing, means for adjusting said chamber horizontally and vertically with respect to the drum, means for holding said suction chamber fixed in any given position with relation to the drum, means for rotating said drum, and a baffle plate arranged within the casing and upon which the material conveyed from the drum is deposited, said drum having an outlet at one end, and a trough arranged beneath said outlet to receive the material passing through the drum.

2. An ore concentrating machine comprising a casing, a drum mounted thereon for rotation and having its inner surface roughened, and adapted to receive the material to be dealt with, means for creating suction in said casing, means operated from the aforementioned means for slowly rotating said drum, a perforated suction chamber adjustably mounted in said drum and communicating with said casing, whereby the lighter material is conveyed from the drum into the casing, said drum being tapered toward one end, the opposite end being open for the discharge of the material passing through the drum, a trough arranged beneath the outlet end of the drum, a dust shield arranged in juxtaposition to said end and carried by the suction chamber, and a baffle plate within the casing and upon which said material drawn into the suction chamber is deposited when conveyed to said casing.

3. An ore concentrating machine comprising

ing a casing, a drum mounted for rotation thereon and adapted to receive the material to be dealt with, said drum having its inner surface roughened, and tapered toward one 5 end which is closed, the opposite end of the drum being open, a hopper, a supply tube leading from the hopper into the drum through the closed end thereof, a valve controlled communication between the hopper 10 and said tube, a spreader apron arranged within the drum immediately beneath the adjacent end of said tube, a spreader arranged interiorly on said drum, means for rotating said drum, means for creating a 15 suction within the casing, a suction chamber adjustably mounted in said drum and communicating with said casing, a baffle plate arranged within the casing and upon which the material conveyed from the drum to the 20 casing is deposited, and a valve mounted on said casing to regulate the suction through said suction chamber.

4. An ore concentrating machine comprising a casing, a drum mounted thereon for rotation, and adapted to receive the material to 25

be dealt with, means for rotating said drum, means for creating a suction within said casing, a suction pipe projecting from said casing, a suction chamber arranged within the drum and supported by said pipe, said 30 chamber including a flat top and a curved corrugated and perforated bottom, means permitting said suction pipe to be adjusted vertically to vary the position of the suction chamber within said drum, means whereby 35 said chamber can be adjusted longitudinally of the drum and with relation to said suction pipe a valve on said casing for regulating the suction created in the suction chamber, and a baffle plate arranged within the 40 casing and upon which the material conveyed from the drum through the chamber into the casing is deposited, said casing having an outlet opening, and a normally closed cover for said opening and connected with 45 the baffle plate to be automatically opened as described.

In testimony whereof I affix my signature.

PHILIP F. REINHART.
